UNITED STATES PATENT OFFICE.

AXEL WELIN, OF LONDON, ENGLAND.

DAVIT.

No. 872,776.

Specification of Letters Patent.

Patented Dec. 3, 1907.

Application filed May 27, 1907. Serial No. 375,913.

To all whom it may concern:

Be it known that I, AXEL WELIN, engineer, a subject of the King of Sweden, residing at Hopetoun House, Lloyds avenue, in the city 5 of London, England, have invented new and useful Improvements in and Relating to Davits, of which the following is a specification.

This invention relates to the well known 10 form of davit the lower part of which is in the form of a toothed quadrant rolling upon a rack.

In such davits as heretofore constructed difficulty has sometimes been experienced 15 by the racks and guides becoming choked especially by ice.

According to this invention this objection is overcome by making the rack in the form of a grating and by providing at each side of 20 the rack a guide projecting above it. With such an arrangement any ice that may form is crushed and forced through the teeth of the rack.

Figure 1 is a side elevation and Fig. 2 a 25 back elevation of a davit constructed according to this invention. Fig. 3 is a side elevation and Fig. 4 is a plan of part of the rack. Fig. 5 is a local section on the line 5—5 Fig. 3. Fig. 6 is a side elevation and Fig. 7 a 30 front elevation of part of the quadrant. Figs. 3 to 7 are to a larger scale than Figs. 1 and 2.

a is the davit the lower part *b* of which is in the form of a toothed quadrant.

The davit *a* works on a pivot pin *c* fixed to 35 the side of a block *d* which is free to move along a guide bar *e*. The lower part of the block *d* is in the form of a nut through which the screw *f* passes.

g is a handle on the screw *f* and *h* is the 40 rack upon which the quadrant *b* is rolled to and fro by turning the screw.

The rack *h* (shown to a larger scale at Figs. 3 to 5) consists of teeth *j* having their ends fixed to two side guide plates *k* which project above the teeth. The teeth *j* as shown have 45 clear openings between them and the quadrant *b* (shown to a larger scale at Figs. 6 and 7) rolls between the guide plates *k* so that any ice that may be formed on the parts is crushed and forced through the openings. 50 The openings between the teeth, *j*, flare downwardly, *i. e.*, they gradually increase in width from their upper portions toward their lower ends, thus enabling the crushed ice to more readily pass through the rack. 55

What I claim is:

1. The combination of a davit, a toothed quadrant at the bottom of the davit and a horizontal rack beneath the toothed quadrant having clear openings through it between its teeth upon which the quadrant can roll, crush ice and force it through the openings. 60

2. The combination of a davit, a toothed quadrant at the bottom of the davit and a horizontal rack below the quadrant having clear openings between its teeth which flare or increase in width downwardly from their upper portions towards their lower ends upon which the quadrant can roll and force ice 70 through the openings.

3. The combination of a davit, a toothed quadrant at the bottom of the davit, a horizontal rack below the davit having clear openings between its teeth upon which the quadrant can roll and crush ice through the openings and guide plates at each side of the rack projecting above its teeth. 75

AXEL WELIN.

Witnesses:

ALFRED NUTTING,
PERCY PHILLIPS.
